UNITED STATES PATENT OFFICE

ELIHU D. WATT, OF LA GRANGE, ILLINOIS, ASSIGNOR TO RAYMOND CONCRETE PILE COMPANY, OF NEW YORK, N. Y., A CORPORATION OF NEW JERSEY

CONCRETE PILE SHELL

Application filed September 26, 1929. Serial No. 395,255.

This invention pertains to shells for concrete piles, of the kind in which a thin metallic shell is lined with waterproof material such as concrete, and in which reinforcing wires are embedded in the concrete.

In previous practice the wires have been completely embedded in the concrete shell lining so that the driving core necessarily made contact with the concrete during the driving operation.

According to the present invention the reinforcing wires are only partially embedded in the concrete lining so that all contact between shell and driving core is metal to metal instead of the inappropriate metal to concrete contact obtained in former designs.

Another object of the invention is to obtain a more intimate bond between the concrete shell and the subsequently poured concrete core than has been previously accomplished. This is possible because the wires of the shell, protruding therefrom, become partially embedded in the concrete core of the pile, thereby providing a reinforcing interlock between the concrete shell and concrete core.

A further object is to provide a reinforced concrete driving shoe for the shell, to replace the metal type of shoe previously used.

Further and other objects and advantages will be apparent from the specification and claims, and from the accompanying drawing which illustrate what is now considered the preferred embodiment of the invention.

Fig. 1 shows a concrete boot and shell according to the present invention, on a collapsible driving core ready for driving.

Fig. 2 is the same as Fig. 1 after removing the driving core and filling the shell with plastic concrete to form the concrete core.

Fig. 3 is an enlarged detail of Fig. 1.

Fig. 4 is an enlarged detail of Fig. 2.

In Fig. 1, 10 is a tapered collapsible driving core of familiar type, the leaves or plates of which, at their lower ends, are shaped to fit the interior of the driving shoe 12, which is formed of a concrete body faced on the inside and outside by thin metal casings or coating 14 and 16, respectively. Casings 14 and 16 are very thin and are placed in the

mold in which the concrete is poured, thereby obtaining such intimate contact between concrete and metal that the shoes have been found to be almost immune from failure by shattering, which has been a shortcoming of previous concrete shoes.

The concrete shell is built up in sections, each comprising a thin metal casing 18, a concrete body 20, and rings or coils of wire 22 partially embedded in concrete 20. As will be seen in enlarged detail view Fig. 3, there is no contact between driving core 10 and the concrete lining 20, the only contact of the core being with rings 22.

As is well known in the art, the driving core and shell are driven to proper depth in the ground while arranged as in Fig. 1. The core is then removed and the shell filled with plastic concrete 24 which, when set, forms with the shell a monolithic pile structure (Fig. 2).

The enlarged detail of Fig. 4 shows how the reinforcing rings 22 are, in the finished structure, embedded partially in the concrete 20 of the shell and partially in the concrete 24 of the pile core, thereby assisting in forming the bond between them.

It is to be understood that the invention is not limited to the specific embodiment herein illustrated and described but may be used in other forms without departure from its spirit as defined by the claims which follow.

I claim—

1. A pile shell adapted for driving on a driving core, comprising in combination, a hollow monolithic concrete body and reinforcing rings arranged in spaced relation on the inner side of said body throughout its length and having a portion thereof embedded in said concrete body and a portion exposed for contact with the driving core whereby the driving core is prevented from making contact with the concrete of the body, said rings held in spaced relation by said concrete body.

2. A pile comprising in combination, a concrete monolithic shell, a concrete monolithic core within said shell, and reinforcing rings partially embedded in said shell and said core, and held in spaced relation by the

shell during driving and forming an interlock between said shell and core in the completed pile.

3. A driving shoe for a pile, comprising in combination, a concrete body portion and reinforcing members therefor comprising thin metal casings on the outside and inside of said concrete body closely fitting same, substantially as described.
- 10 4. A driving shoe for a pile, comprising in combination, a cup-shaped concrete body and reinforcement therefor comprising a thin metal coating applied directly to the inner and outer surfaces of said body.
- 15 In testimony whereof I hereto affix my signature.

ELIHU D. WATT.
